UNITED STATES PATENT OFFICE.

HERBERT PEARCE, THOMAS ROBERT GILLETT PARKER, AND FRED WESLEY WRIGHT,
OF BROADHEATH, ENGLAND, ASSIGNEES TO LINOTYPE AND MACHINERY LIMITED,
OF LONDON, ENGLAND.

CONTROL OF THE TRIPPING MECHANISMS OF A PRINTING-PRESS.

1,142,268.

Specification of Letters Patent.

Patented June 8, 1915.

Application filed July 22, 1912. Serial No. 710,884.

To all whom it may concern:

Be it known that we, HERBERT PEARCE, THOMAS ROBERT GILLETT PARKER, and FRED WESLEY WRIGHT, subjects of the King of 5 the United Kingdom of Great Britain and Ireland, residing at Linotype and Machinery Works, Broadheath, in the county of Chester, England, have invented Improved 10 Control of the Tripping Mechanisms of a Printing-Press, of which the following is a specification.

Printing presses having automatic mechanisms for tripping and untripping certain of their organs, such as the impression cylinder, the rollers that ink the form or plate cylinder, and the damper of the plate cylinder, are well known. But each mechanism is characterized by the draw-back that it is controlled by a hand lever, or equivalent, 15 limited to it, and that all these levers present themselves in different positions distributed about the press and entirely independent of each other, so that the attendant must, to manipulate them, move from one to 20 the other.

The object of the present invention is to obviate the consequences of this drawback and the invention itself consists in bringing the several controlling levers of the inking 25 rollers, the ink ductor roller, the water ductor roller, or of any other organ which has to be tripped manually and occasionally, into a grouped position within easy reach of the feeder from his position on the foot-board because he may find himself called 30 upon at any moment to manipulate any of the said levers, as well as within easy reach of the attendant from the position which he will occupy when he is attending to the 35 forms or plate, because it is at such times that manipulation of the levers by him will be necessary, and, in connecting them all, after they have been so brought together, to 40 the tripping mechanism of another organ 45 which mechanism is independently operated, either automatically or manually.

Let it be assumed that the tripping mechanisms to be controlled are those of the damper and the ink ductor roller, and that 50 the other organ above mentioned is the set of inking rollers and is tripped and untripped automatically.

The accompanying drawing is a side ele-

vation illustrating the invention generally and, in particular, a preferred form of its 55 application to the two mechanisms and one organ just mentioned.

Referring to it, 1 is the base of the machine; 2, the form or plate cylinder; 3, 3 slotted arms to support the bearings of the 60 inking rollers for the cylinder 2; 4, a ring at each end of the cylinder 2 and to which the respective arms 3 are fast and which rings are reciprocated about a shaft 5 to trip and untrip the said rollers, by arms 6. These 65 arms are reciprocated from an automatically reciprocated shaft 7 through an arm 8, a link 9, an arm 10, a shaft 11, arms 12 and links 13. Neither the combination of parts 3 to 6 nor of 7 to 13 form *per se* any 70 part of the present invention. 14 is the water fountain and roller; 15, the water ductor; 16, the frame vibrating the ductor 15 about the axis of a stud or shaft 17 between the water fountain roller 14 and the vibrator 75 roller 18; and 19, 19, the dampers together constituting the damper. One well known means of tripping the damper consists of a cam 20 rocked by an external hand lever (not shown) about an axis 21, and restricted 80 in its scope to doing this, into the path of the vibrating frame 16 of the water ductor 15, thereby holding the latter out of contact with the water fountain roller 14. An 85 equally well known means of tripping the ink ductor roller consists of a rocking hook on the top of a link 22 that is likewise worked by an external hand lever restricted in its scope to doing this, and which hook is moved into the path of a spring protruded 90 finger on the vibrating frame of the said roller, so as to engage with it when the latter is in contact with the ink distributing drum, locking it in this position and so stopping the ink supply. Only the link 22 of 95 this ink ductor roller trip is included in the drawing.

According to the preferred form above mentioned, 23 is a bell crank lever fulcrumed at 24 on the feeder side frame of 100 the press and in front of the inking roller trip mechanism. One arm of it is pivotally connected as at 25 to the link 9 of that mechanism while the opposite one hangs downward. As to the damper, 26 is a bar pivotally connected by one end to the cam 20 (but 105

- on the opposite side of its axis 21) and prolonged by the side of the said side frame toward and just past the front end of the press where it terminates in a hand grip 27.
- 5 28 is a stud projecting laterally from the hanging arm of the lever 23 and 29 a notch in the bottom edge of the bar 26, so that when the notch is engaged on the stud, the cam 20 is operatively connected with the 10 inking roller trip mechanism with the result that the damper will be tripped and untripped by it, so long as the said notch and stud remain engaged.
- 15 30 is a second stud on the said side frame and 31 a second notch in the bottom edge of the bar 26, both so positioned that the engagement of the notch 31 on the stud 30 trips the damper and holds it tripped.
- 20 32 is a third stud so positioned on the same side frame that engagement of the notch 31 with it, untrips the damper and holds it untripped. And as to the ink ductor roller, 33 is a bell crank lever fulcrumed on the same side frame as the lever 23, as at 25 34, in front of the link 22 and having one arm pivotally connected to the bottom end of the latter, the other arm hanging downward. 35 is a bar pivotally connected by its rear end to the outer end of the said downwardly hanging arm and prolonged in exactly the same way as the bar 26 and likewise terminating in a similar grip 36. Thus 30 both grips are distinct from each other and both are positioned so as to be within both 35 view and reach of feeder and of attendant. The bar 35 has three notches 37, 38 and 38^a in its bottom edge, the first coöperating with a stud 39 on the downwardly hanging arm of the lever 23 in the same way as the notch 29 with the stud 28, and the two latter with the stud 40 in a similar manner. So long as either or both bars 26, 35, are connected to the lever 23, so long will the respective tripping mechanism partake of the tripping and untripping movements of the shaft 7, and so long as either or both the said bars are disconnected from the said lever 23, so long will the respective tripping mechanism remain at rest in the tripped or untripped 45 position according to which of the studs 30 or 32 is engaged with notch 31 in bar 26 in the one case, and which of the notches 38^a or 38 in bar 35 is engaged with stud 40 in the other case. The lower end of link 22 is 50 formed with a slot 22^a, the object of which is to prevent release of the ink ductor trip when bar 35 is engaged with stud 39, until the high part of the cam which rocks the ink ductor lever shaft and levers has reached its operative position, when the link 22 will fall to its lowest position by gravity. Otherwise, the release of the ink ductor trip by reason of its connection with the ink roller trip occurring at a moment when the low 55 part of the said cam is in the operative posi-

tion, allows the ink ductor roller to bump on to the fountain roller. Both the cam, the shaft, and levers just mentioned are too well known in the art to require further description.

The illustrated plurality to be controlled comprises only two automatic tripping mechanisms but may, and according to the invention, does, comprise as may such mechanisms as there are in the press less the one, as the inking roller tripping mechanism, to which they are temporarily connected. Thus both the feeder and the attendant, each acting on his own initiative as suggested by his respective duties, has grouped within his reach and control, each and all of a plurality of the automatic tripping mechanisms to the extent of manually putting any or all of them into either the tripped or the untripped position or of connecting them with an independent automatic tripping mechanism.

Having described our invention, we declare that what we claim and desire to secure by Letters Patent is:

1. In a printing press, a plurality of 90 automatic tripping mechanisms capable of being tripped independently of each other and occasionally; a tripping mechanism operated automatically during each normal cycle of the press, independently of any one 95 of the plurality above mentioned; means grouping the said plurality within easy reach and control of either the press feeder or the press attendant when in their respective normal working positions; means 100 by which any or all of the said plurality can be manually tripped or untripped; and means by which any or all as aforesaid can be connected to the automatically operated tripping mechanism aforesaid. 105

2. In a printing press, a plurality of 110 automatic tripping mechanisms capable of being tripped independently and occasionally; a tripping mechanism operated independently of any one of the plurality above mentioned; a bar from each of the plurality of mechanisms to be tripped; a grip presented by it clear of the press frame and in the immediate neighborhood and practically parallel with all the other grips so 115 presented; a detachable connection between each of the said bars and the independently operated tripping mechanism; and a detent to hold the respective bar in its detached position. 120

3. In a printing press, the combination of a plurality of tripping mechanisms operating automatically during the normal working of the press, manually operable means for controlling the operation of each 125 of said mechanisms, and manual and detachable means for temporarily connecting said controlling means so that they may be automatically operated conjointly.

4. In a printing press, the combination 130

of a plurality of tripping mechanisms operating automatically during the normal working of the press, manually operable means for controlling the operation of each of said mechanisms, a tripping mechanism operated automatically during each normal cycle of the press and independently of the mechanisms above mentioned, and manual and detachable means for temporarily connecting the independently operated mechanism with one or more of the controlling means as desired.

5 5. In a printing press, the combination of a plurality of automatic tripping mechanisms, an independently operated device operating automatically during each normal cycle of the press, and manually operable means for controlling the operation of each of the tripping mechanisms and detachably connected to said device; whereby the tripping mechanisms may be operated by the

10 controlling means either independently or automatically and conjointly, as desired.

15 6. In a printing press, the combination of a plurality of tripping mechanisms operating automatically during the normal working of the press, and manually operable devices connected with said mechanisms respectively, said devices being extended to and grouped at a common point 25 within easy reach of the operator; whereby the said devices may be operated independently or may be conveniently connected together for conjoint automatic operation.

20 In witness whereof we have hereunto set 30 our hands in the presence of two witnesses.
